US00D986984S

(12) United States Design Patent (10) Patent No.: US D986,984 S
(45) Date of Patent: * May 23, 2023

(54) HILT FOR LIGHT SWORD

(71) Applicant: NINGBO CASCENT INTERNATIONAL TRADE CO., LTD., Zhejiang (CN)

(72) Inventor: Makiyo Tang, Zhejiang (CN)

() Term: 15 Years

(21) Appl. No.: 29/735,935

(22) Filed: May 26, 2020

(51) LOC (14) Cl. 21-01

(52) U.S. Cl.

USPC D21/567; D21/568

(57) CLAIM

The ornamental design for a hilt for light sword, as shown and described.

DESCRIPTION

FIG. 1 is a front elevational view of a hilt for light sword showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines in the drawings depict portions of the hilt for light swords that form no part of the claim.

1 Claim, 4 Drawing Sheets
